(57) **CLAIM**

The ornamental design for a noise monitor having a handle, as shown and described.

DESCRIPTION

FIG. 1 is a perspective view of a noise monitor having a handle showing the new design.

FIG. 2 is a side view thereof;

FIG. 3 is a bottom view thereof;

FIG. 4 is a top view thereof;

FIG. 5 is a front view thereof; and,

FIG. 6 is a rear view thereof.

The broken line showing of structural features is included for the purpose of illustrating non-claimed subject matter and forms no part of the claimed design.

1 Claim, 4 Drawing Sheets
